UNITED STATES PATENT OFFICE.

GEORGE McCRAE, OF BRANTFORD, ONTARIO, CANADA.

CYLINDRICAL KILN AND DRIER.

1,399,503.

Specification of Letters Patent.

Patented Dec. 6, 1921.

Application filed October 6, 1920. Serial No. 415,199.

To all whom it may concern:

Be it known that I, GEORGE McCRAE, of the city of Brantford, in the county of Brant, Province of Ontario, Canada, have 5 invented certain new and useful Improvements in Cylindrical Kilns and Driers, of which the following is a specification.

This invention relates to cylindrical kilns, usually rotary, in which solid materials are 10 subjected to the action of heat, and particularly to kilns for operating on materials which, in whole or part, require to be dried or preheated before entering the kiln, and my object is to devise a kiln which, without 15 any increase in length, is adapted to preheat such material.

I attain my object by employing a kiln having longitudinal external ribs, such for example as the kiln described and shown in 20 my Canadian patent application No. 240053 filed April 14th, 1920, and by securing an outer sectional shell outside the kiln to form an annular preheating space outside the kiln, such sectional shell being provided with 25 flanges secured to the ribs aforesaid.

The kiln is hereinafter more specifically described and illustrated in the accompanying drawings in which—

Figure 1 is a side elevation, partly broken 30 away, of my cylindrical kiln;

Fig. 2 a cross section on an enlarged scale of part of the kiln; and

Fig. 3 a side elevation, partly in section, of part of the kiln on the same scale as 35 Fig. 2.

In the drawings like numerals of reference indicate corresponding parts in the different figures.

The kiln, as will be seen from Fig. 1 of 40 the drawings, is in general of ordinary type, and is shown as adapted for rotation, 1 being the circular tracks commonly employed and 2 the sheaves or pulleys whereby power may be applied to rotate the kiln. Of 45 course, any ordinary gearing may be employed for this purpose. As indicated particularly in Figs. 2 and 3 of the drawings, the kiln, instead of being made of lapped and riveted plates, is formed of a plurality 50 of longitudinal sections 3, each section being provided along each of its straight edges with a radial flange 4, these flanges extending outwardly a sufficient distance to provide suitable space for the bolts or rivets by 55 which they are secured together.

To the interior of the shell the refractory

lining 5 will be secured in any ordinary manner.

Outside the kiln, between any two of the circular tracks 1, I secure a cylindrical casting, preferably formed of sections 6. This sectional shell may be secured to the kiln in any suitable manner. I prefer, however, to secure the shell to the ribs or flanges 4, the external shell being provided with flanges 7, which may be riveted or bolted to the flanges 4. In the preferred construction each section is provided with an inwardly turned flange 7 secured to one of the flanges 4 and an outwardly extending flange 8, the 70 flanges 8 of two adjoining sections being in juxtaposition and bolted or riveted together. This external shell is preferably formed as a truncated cone to facilitate discharge of any material introduced into the space between the two shells to be dried or preheated. This necessarily means, of course, that the flanges 7 taper in the direction of their length. Despite the fact of lining the kiln, a good deal of heat is conducted to the outer 80 surface of the kiln and is there radiated and lost. With my construction, I am enabled to utilize this otherwise waste heat to preheat or dry any of the products which are subsequently to be introduced into the 85 interior of the kiln, and my invention is particularly adapted for use in cement kilns to preheat part or all of the constituents of which the cement is manufactured.

To permit of the escape of moisture laden 90 air I provide vents 9 in the external shell 6. These air vents are preferably formed as pipes having their inner ends bent in the direction of the flow of material in order to prevent leakage of the latter.

What I claim as my invention is:—

1. A cylindrical kiln comprising a metallic shell; annular members longitudinally spaced apart and secured to the shell for supporting or rotating the latter; and an external sectional shell secured to and spaced from the kiln shell and intermediate two adjacent members.

2. A cylindrical kiln comprising a metallic shell having external longitudinal ribs 105 formed thereon; annular members longitudinally spaced apart and secured to the shell for supporting or rotating the latter; and an external sectional shell secured to said ribs and spaced from the kiln shell and intermediate two adjacent members.

3. A cylindrical kiln comprising a metallic

- shell; an external shell secured to the kiln shell and spaced therefrom, the external shell being shaped substantially as a truncated cone.
- 5 4. A cylindrical kiln comprising a metallic shell having external longitudinal ribs formed thereon; an external sectional shell spaced from the kiln shell and secured to said ribs.
- 10 5. A cylindrical kiln comprising a metallic shell having external longitudinal ribs formed thereon; an external sectional shell spaced from the kiln shell and having flanges on the sections secured to the ribs.
- 15 6. A cylindrical kiln comprising a metallic shell having external longitudinal ribs formed thereon; an external sectional shell spaced from the kiln shell and having flanges on the sections secured to the ribs.
7. A cylindrical kiln comprising a metallic shell; an external shell secured to the kiln shell and spaced therefrom; a bent pipe mounted in the external shell communicating with the space between the shells, the inner end of the pipe being bent to face in the direction of the flow of material in the space.

Signed at city of Brantford, this 19th day of August, 1920.

GEORGE McCRAE.
